METHOD OF REFINING GLYCERIDE-TYPE OILS

Benjamin Clayton, Sugarland, Tex., assignor to
Refining, Inc., Reno, Nev., a corporation of
Nevada

Application January 4, 1937, Serial No. 119,022

20 Claims. (Cl. 260—426)

My invention relates to a novel method and apparatus for refining glyceride-type oils, and has among its objects the lowering of refining losses without increasing the color of the refined oil, in many instances producing an oil of better color, as evident either by the refined oil when first separated or after conventional washing, drying and bleaching thereof.

A crude glyceride-type oil contains free fatty acids and other impurities. For example, crude cottonseed oil may contain free fatty acids ranging in quantity from a fraction of one percent to more than two percent. It is common practice to refine such glyceride-type oils by use of an alkali refining agent, usually in dilute aqueous solution, such as caustic soda or caustic potash. These and other refining agents capable of reacting or combining with the impurities to form foots and thus refining the oil are herein included in the term "refining reagent".

While such refining reagents have a preferential affinity for the free fatty acids, they also tend to react with the oil itself. The loss in volume of a crude glyceride-type oil during such refining is called the "refining loss". It is made up partly of the loss due to the formation of foots from the free fatty acids and other impurities initially in the oil, a necessary loss, and partly of the loss due to the action of the reagent on the oil itself and the entrainment of neutral oil with the separated foots, a loss which is very materially decreased in the present invention. It is almost invariably the practice to add a greater quantity of the refining reagent than is theoretically necessary to neutralize the free fatty acids, the excess acting to produce a proper bleach by removing objectionable color. However, in conventional batch treatment this excess tends to saponify a portion of the neutral oil, thus increasing the refining loss.

In reacting or combining with the impurities, the refining reagent forms foots or soapstock. These foots are composed primarily of soap and various color impurities and are in the form of minute particles which tend to settle if allowed to stand quiescent. Oil may be associated therewith either by being emulsified within the particles, or by being entrained in the voids between such particles. Usually both types of association may coexist, especially if gravitational separation is utilized. In a continuous refining system utilizing a centrifuge for separating the oil and the foots it is possible to recover most of the oil in these voids, but the present inven-

tion goes even further in seeking to eliminate in addition losses due to the emulsified oil.

I have found it possible to decrease very materially saponification of neutral oil and reduce the amount of oil in the soapstock without increasing the color of the refined oil, even often producing an oil of better color, by proper use of a third material. This material is an agent which acts, in the quantities used, as a de-emulsifying agent and as an inhibitor for saponification of neutral oil, being hereinafter termed a "de-emulsifying and inhibiting agent". It is preferably volatile and has a tendency to break or prevent the formation of the usual uniformly emulsified character of the soapstock. Its power to inhibit the saponification of neutral oil is of particular importance as it reduces this saponification loss one half or more. It may desirably be of such character as in effect to "grain out" color impurities.

Only sufficient quantity of this agent is used to inhibit saponification of neutral oil by the excess of the refining reagent employed, and to exert the desired de-emulsifying action. This quantity is preferably small, seldom exceeding more than a few percent and usually being between .75% and 1.7% based on the weight of the oil, though these limits are not invariable and may be departed from, being here set forth by way of illustration. With exceptional oils containing large amounts of fatty acids, for example, above 3%, it may be necessary to increase somewhat proportionally the quantity of the de-emulsifying and inhibiting agent.

The alcohols have been found very satisfactory as such a third agent, though various other chemical agents may be used. Monohydric or polyhydric alcohols may be used, but the former is preferred. For example, butyl, iso-propyl, propyl, amyl, ethyl or other monohydric alcohols give satisfactory results, those most miscible with water being preferred, for example, iso-propyl or ethyl. Iso-propyl alcohol has been found to be particularly advantageous. The term "alcohol" hereinafter used represents one example of a de-emulsifying agent and includes alcohols of the monohydric or polyhydric types, or mixtures thereof.

Various chemical agents other than alcohol can also be used as the de-emulsifying and inhibiting agent. Various of the esters can also be employed, for example, ethyl acetate, or the refining reagent may comprise sodium alcoholate, potassium alcoholate, etc.

The de-emulsifying and inhibiting agent may be added by mixing with the refining reagent, or it may be added to the oil before or after addition of this refining reagent. The first-mentioned system is preferred, the resulting refining solution usually containing from 10 to 25% of the alcohol, or other de-emulsifying and inhibiting agent, though these limits can often be departed from. For instance, with grain alcohol it is possible to use even more alcohol than water in the solution. With iso-propyl alcohol it is usually desirable that the solution of alcohol and refining reagent contain not more than 15% thereof, though slightly more and up to 25% can be used.

It is an object of the present invention to reduce saponification of neutral oil in a batch or continuous process for refining glyceride-type oils, and to produce other desirable results in such a process.

It is another object of the present invention to refine glyceride-type oils by use of a refining reagent and an agent inhibiting saponification of neutral oil and acting as a de-emulsifying agent to reduce the amount of oil in the soap stock.

It is a further object of the invention to add and subsequently remove this de-emulsifying and inhibiting agent in such a process.

While batch operation of the invention is quite successful, I have found particularly good results and excellent economies in operating in a continuous manner. Any difficulty which may be experienced during batch treatment in uniformly mixing alcohol, for instance, with a large body of oil can be overcome in a continuous process by mixing small quantities of the three materials, preferably by continuously mixing suitably proportioned streams thereof. If this mixing is done in a confined space there is no loss due to evaporation, and other very desirable ends are accomplished. The mixing action can be made very complete and the resulting mixture can be moved from the mixing zone as fast as it is formed.

It is an object of the present invention to add to one portion of a continuous refining system a de-emulsifying and inhibiting agent and to remove this agent at another portion of the system.

Another object is to mix small quantities of the materials, preferably by mixing proportioned streams thereof.

Another object of the invention is to move the resulting mixture from the mixing zone as fast as produced, preferably as a stream moving with such flow conditions that stratification or separation of the materials is prevented, thus insuring delivery of a uniform mixture to the separating means.

A proper excess of the refining reagent is preferable in the process over and above the amount theoretically required to combine with the free fatty acids, the excess being that customarily used and acting on the color impurities. The removal of such color impurities is a function of time, and while with certain oils this reaction is very rapid, some oils require a longer time of contact with this excess refining reagent.

Heat may accelerate this color-removing reaction and facilitate later separation of the mixture. In the present invention flow of the mixture through an elongated zone will give this additional time, if required, and heat may be applied during this flow if desired.

It is an object of the present invention to mix a glyceride-type oil, a refining reagent and a de-emulsifying and inhibiting agent and condition the resulting mixture during flow through a passage before separating any of the materials in the mixture from the remaining materials there-

It is not difficult to separate the refined oil, the foots, and the de-emulsifying and inhibiting agent. Several alternatives can be used, and these products can be separated in various sequence. The resulting reaction products can be so treated as to first remove the de-emulsifying and inhibiting agent, for instance by vaporization, and it is an object of the present invention to first separate the de-emulsifying and inhibiting agent, leaving a mixture of refined oil and foots which is later separated.

Another object of the invention is to add a vaporizable agent to one portion of a refining system, then separate this agent by vaporization and subsequently separate the refined oil from the foots by any suitable system.

It is a further object of the invention to introduce the reaction products into a vaporizing zone which may form a part of the confined space, and there separate this agent in vapor state, heat being applied either before and/or after the products enter this chamber. Heat applied ahead of this chamber may be supplied to one or more of the materials before mixing or may be supplied to the mixture. The controlling factor is that sufficient heat be used to vaporize this agent under the pressure conditions existing in this chamber, and a vacuum may be maintained therein if desired.

Another object of the invention is to provide a method in which the foots can be at least partially dehydrated, if desired, prior to separation from the refined oil. In this connection, the invention is not necessarily limited to the use of alcohol or similar de-emulsifying and inhibiting agent, for even if a material such as alcohol is not used, I have found it desirable in many instances to evaporate water from the mixture of foots and refined oil thus removing at least a part of the water and thus dehydrating the foots at least partially. By substantially completely dehydrating the foots it is possible to stop immediately any further tendency toward saponification of neutral oil, for by dehydrating the foots the ionizing power of the caustic in solution is removed, thus preventing any further tendency to saponify neutral oil. Further, the refined oil in the presence of dehydrated foots is much more stable and can be kept in this condition without splitting or rancidity which tend to take place in the presence of water. It is thus a feature of the present invention that water may be removed partially or completely from the reaction products, regardless of whether or not a de-emulsifying and inhibiting agent such as alcohol is used in the process.

It is a further object of the invention to continuously withdraw the refined oil and foots from the vaporizing zone, and to subsequently separate these materials by any suitable means such as gravitational or centrifugal separating devices, filtration, etc.

With certain types of separation, it is desirable to effect this separation while water is present and associated with the foots. It is an object of the present invention to provide this water either by not completely dehydrating the

feet, or by adding additional water to the foots prior to the separation step.

When utilizing certain methods of separating the de-emulsifying and inhibiting agent, such as alcohol, from the other materials, it has been found that the resulting refined oil has not been harmed as to color by the presence of the de-emulsifying agent. In fact, an oil of much better color has been produced in many instances, the alcohol or other de-emulsifying and inhibiting agent apparently acting to "grain out" the color so that it dissolves in the water, apparently being no longer oil-soluble to any great degree. In all probability, the alcohol acts as a peptizing agent in dissolving out, or combining with, the soluble coloring matter, preventing subsequent entanglement thereof with the oil.

However, when separating the de-emulsifying and inhibiting agent by delivering the reaction products to a low-pressure vaporizing zone, there may be a tendency for the color to be set thus making more difficult the production of a refined oil of the desired color. This phenomena is not always present but is noticeable on certain oils, especially where the excess refining reagent has not had sufficient time to act upon the color impurities. Any such difficulty may be overcome, and the complete process made even more effective, by preliminarily treating the oil to remove gums and mucilaginous matter. With these removed, it is possible to readily obtain refined oil of acceptable color, and often of a much better color than produced by conventional processes.

It is an object of the invention to de-gum a glyceride-type oil preparatory to refining and subsequent separation of water or a de-emulsifying and inhibiting agent, or both, by vaporization.

Various other objects and advantages will be made evident to those skilled in the art from the following description illustrative of ways and means for performing the process.

The drawing represents a pipe line diagram of a complete refining system incorporating the features mentioned above.

Fig. 1 diagrammatically shows a complete system capable of preliminarily treating the oil to remove gums and mucilaginous matter preparatory to refining. The particular de-gumming system diagrammatically shown in Fig. 1 is very satisfactory in this regard but is not per se a part of the present invention, being claimed in the copending application of Benjamin H. Thurman, Serial No. 6,446 entitled "Method of treating vegetable oils and product obtained thereby." Various systems, either batch or continuous, may be used in this capacity, through the continuous system shown is particularly desirable in conjunction with the subsequent refining equipment.

As shown in Fig. 1, the crude glyceride-type oil may be supplied to a tank 1, usually after preliminary filtration to remove fibrous materials or solids. The de-gumming reagent in tank 2 may comprise water, alcohol, or any electrolyte such as dilute aqueous solutions of acids, alkalis, or salts used in amounts set forth in the application supra. A ten percent boric acid solution gives excellent results. This preliminary treatment, if used, is designed to remove gums and mucilaginous matter, not to react with the free fatty acids of the oil.

75 A pump 3 may continuously withdraw oil

from the tank 1, delivering a stream thereof to pipe 4. A pump 5 may deliver a proportioned quantity of the de-gumming reagent to the pipe 4, being connected to the pump 3 by a variable speed mechanism 5a. These materials are intimately mixed together by any suitable mixing means, injection of one liquid into a stream of another having been found entirely satisfactory in this regard. The quantity of de-gumming reagent is preferably from 1 to 10 percent of the oil, by volume, though larger quantities of the de-gumming reagent may be used.

The mixture is heated in a heater 6 shown as including a coil 7, positioned in a container through which a suitable heating medium is circulated, the temperature being raised to a degree facilitating centrifugal separation when the mixture is introduced into a centrifuge 8. Here the reaction products are separated into de-gummed oil, delivered through a spout 9, and a material containing the gums, mucilaginous matter and other impurities of similar character. The de-gummed oil enters a tank 10 and may be withdrawn therefrom at a rate corresponding to the rate of introduction. It will be clear, however, that if this preliminary treatment is not desired, the crude glyceride-type oil can be moved directly into the tank 10.

A tank 11 may contain a body of the refining reagent, and the alcohol or other de-emulsifying and inhibiting agent may be retained by a tank 12. If desired, any or all of these three materials may be preliminarily heated in their respective tanks or may be heated in pre-heaters 10a, 11a, and 12a, before being mixed. Such preliminary heating is not necessarily used but offers one valuable way of controlling the temperature conditions in the system. If heat is applied to one or more of the three materials before mixing, particularly to the oil, it will facilitate pumping and may be used to increase the effectiveness of the later steps in the process. Even if the oil is pre-heated, it is not necessary in all instances to pre-heat the refining solution and the alcohol or other de-emulsifying and inhibiting agent. If pre-heating thereof is desired the degree of this pre-heating should preferably not be sufficient to vaporize these materials.

By way of illustration, and for exemplary purpose only, the process will be described with reference to continuous operation, and with reference to alcohol as the de-emulsifying and inhibiting agent, the refining reagent being an aqueous alkali solution.

In a continuous process, it is desirable to mix the three materials in proportioned quantities in a confined space closed from the atmosphere. Preferably only small quantities of the materials are mixed at a time, and the mixture is preferably maintained with such flow conditions that the ingredients of the resulting mixture remain uniformly mixed to prevent premature separation. These ends are best accomplished by mixing proportioned streams containing these materials.

For example, proportioning pumps 13, 14 and 15 may respectively draw these materials from the tanks 10, 11 and 12, these materials moving through the pre-heaters, if desired. These pumps may be driven by a drive means 16, preferably of the variable-speed type, and may be interconnected by variable-speed controls 17 and 18 which determine the relative proportions.

With these pumps properly adjusted to supply

proportioned streams to the system a resulting mixture is formed in a mixing zone which may comprise the forward part of a confined space defined in part by a pipe 20 into which the pump 5 13 may directly discharge.

Satisfactory mixing of the three materials can be obtained by suitable introduction of the alkali solution and the alcohol into the pipe 20, either separately or combined to form a refining 10 solution. For instance, the pumps 14 and 15 may separately supply the alkali solution and the alcohol to the pipe 20 through pipes 22 and 23, the alcohol being supplied either upstream or downstream from the point of introduction of the alkali 15 solution. On the other hand, it is often desirable to preliminarily mix the alkali solution and the alcohol to form a refining solution which is then introduced into the oil. This may be accomplished by closing a valve 24 in the pipe 23, 20 and opening a valve 25 so that the pumps 14 and 15 discharge into the pipe 22, the resulting refining solution being then introduced into the pipe 20 to mix with the oil. In other instances, the alkali solution and the alcohol can be preliminarily 25 mixed in the tank 11, the resulting refining solution being pumped through the pipe 22 into the pipe 20 in proportioned quantity.

Various auxiliary mixing devices such as a mechanical mixer can be used if desired, but a satisfactory mixing can be obtained by injection of 30 one material into the stream of another. This minutely disperses the alkali and the alcohol in the oil, forming an excellent mixture and permitting the alkali to act very rapidly on the free fatty acids of the oil so that the resulting foots will be formed while the alcohol is present or immediately preceding the point of introduction of this alcohol. The resulting mixture will include 35 oil, foots, water, alcohol, and any excess of the alkali over and above the amount theoretically necessary to combine with the free fatty acids, this excess acting upon the color impurities during continued flow through the pipe 20. By pumping the materials into such a confined 40 space, the resulting mixture will move from the mixing zone as fast as it is formed. It is preferable to maintain such flow conditions in the confined space that stratification or premature separation of any of the ingredients is prevented.

Flow along a confined space such as is defined by the pipe 20 will give this desirable action, and will condition the mixture preparatory to separation. One phase of this conditioning involves action of the excess alkali on the color 45 impurities. With some oils, this reaction is very rapid in which event the confined space need not be necessarily long to give the desired reaction time. With other oils, a more prolonged time of contact is desirable, and a correspondingly longer confined space is desirable, thus increasing the reaction time before separation.

It is sometimes desirable to heat this resulting mixture during flow through such a confined space. In this capacity I have shown a coil 26 of a heater 27 as forming a part of the confined space, heat being supplied by any suitable means such as a burner 30. Other types of heaters providing a confined space closed from the atmosphere may be utilized, though in some instances no heat need be applied at this point. Flow therethrough should preferably maintain the uniformity of the mixture in the sense that stratification or premature separation is prevented, thus insuring delivery to a separating 50

means of a mixture which does not vary from time to time in composition.

In the embodiments specifically illustrated the resulting products are first subjected to such conditions that the de-emulsifying and inhibiting agent, in this example alcohol, will separate by vaporization, though it will be clear that other methods of separating this agent from the reaction products can be used. In the system shown, the reaction products move through a 10 pipe 31, throttled if desired by a valve 32 or by a nozzle 33, though such a throttling action is not essential. These products are then discharged into a chamber 34 defined by a container of a separating means 35 and comprising 15 a low-pressure zone in the event that a partial vacuum is maintained thereon.

The function of this separating means is to separate the alcohol, and if desired a portion or all of the water, from the resulting reaction 20 products, in a vapor state. In accomplishing this end, it is sometimes desirable to apply heat to this chamber, either by circulating a hot medium through a jacket 36, or by introducing a hot medium such as steam into the chamber 34 by 25 means not shown. If the latter expedient is utilized the partial pressure of the steam will assist separation.

No fixed and invariable figures can be given as 30 to temperatures and pressures in various parts of the system thus far described. These variables will depend upon whether only the alcohol is to be removed by vaporization, or whether in addition a portion or all of the water is to be vaporized. In either instance, the requisite temperatures will depend upon the pressure in the chamber 34. All or a portion of the heat may be supplied during pre-heating, or by heating of the resulting mixture before introduction into the chamber 34, or by heating this chamber itself. 35

As to permissible temperatures of the reaction products entering the chamber 34, I have found that this temperature may be as high as 160° F. or more if desired, without impairing the process and without deleteriously affecting the oil. This is especially true as the oil remains at such temperature for only a short time in the coil 26, the entire flow to the chamber 34 being completed very rapidly, preferably within less than a few minutes. The temperature of the reaction products may be as high as 180° F. or higher, though 40 temperatures considerably higher than 160° F. are not as desirable, and even lower temperatures can often be used, especially if heat is supplied to the chamber 34. By way of example, excellent 45 operation has been obtained by utilization of a temperature of 160° F. in the pipe 31, with a vacuum in the chamber 34 of approximately 26 inches of mercury and some external heat supplied thereto. If the absolute pressure in the chamber 34 is higher, correspondingly higher 50 temperatures may be used. On the other hand, if a higher degree of vacuum is maintained in this chamber, the temperature can be correspondingly lower. If considerable heat is supplied to the 55 chamber 34, as by circulating heating medium through the jacket 36 or introducing steam therethrough, the above temperatures can be materially lower.

If desired, one or more baffles 37 may be mounted in the chamber 34 to move the reaction products through a tortuous path. So also, the liquid collecting in the lower part of this chamber may be mildly agitated to maintain the foots uniformly distributed therein.

The separated vapors may be continuously withdrawn through a pipe 38. If both water and alcohol vapors are removed, these may be fractionally condensed, or they may be condensed together and separated by means well known in the art. In the embodiment illustrated, the pipe 38 conducts the vapors to a condenser 40, moving downward through tubes 41 thereof cooled by a medium circulated exterior thereof. This cooling may condense water vapors, the condensate moving downward in a barometric column 42 with its lower end submerged in liquid in a tank 43. The remaining vapors move through a pipe 44 to a condenser 45 similarly constructed and including a barometric column 46 delivering the condensate, in this instance alcohol, to a tank 47. A vacuum pump 48 is connected to the condenser 45 to maintain the desired low pressure in the chamber 34, the barometric columns 42 and 47 being of sufficient height to balance this low pressure.

The alcohol thus condensed can be moved from the tank 47 to the tank 12 by a pump 49, being thus re-used in the process. Similarly, the water thus condensed may flow, or be pumped by a pump 50 to a tank 51. Here caustic may be supplied through a pipe 52 to prepare the refining reagent which is then moved to the tank 11 by a pump 53.

Assuming that alcohol and some of the water has been removed in the chamber 34, the material in the lower end thereof will comprise a mixture of refined oil and foots which have been at least partially dehydrated. The color impurities, also dehydrated at least partially, will be associated with these foots. This oil-foots mixture is preferably removed continuously from the chamber 34 by any suitable withdrawal means acting in such a manner as not to impair the vacuum in this chamber. Various types of pumps can be used, as diagrammatically indicated by the numeral 68. If desired, this withdrawal means may comprise a barometric column through which the oil-foots mixture moves downward, and being of sufficient height to balance the low pressure in the chamber 34.

This oil-foots mixture may be moved directly to a separating means, or it can be moved through a means indicated by the numeral 69 for increasing, decreasing or maintaining the temperature thereof. By way of example, the mixture may flow through a coil 70 positioned in a container 71 through which a heat-control medium is circulated, the mixture being discharged continuously into a pipe 72. Heat applied at this point will facilitate separation in various separating systems, though in many instances the oil-foots mixture will already be at a temperature satisfactory for separation. On the other hand, better separating action with other separating systems may be obtained if the oil-foots mixture is cooled at this point.

In some instances a better separation can be obtained if the foots are not completely dehydrated, though in other instances dehydration is advantageous. Any desired amount of water can be left in the foots by proper control of temperature and pressure. Alternatively, if the foots have been dehydrated in the chamber 34 it is possible to re-hydrate them to any desired degree. For instance, water may be supplied either as a liquid or vapor to the oil-foots mixture after being withdrawn from the chamber 34. This water may be added either on the intake or discharge sides of the pump means 68. As illus-

trated, a pipe 80 may be used in this capacity, communicating with an intermediate portion of the coil 70. The water introduced at this point will uniformly hydrate the foots, if this expedient is desired.

Various means may be utilized for separating the oil-foots mixture. One very advantageous way is to effect this separation by filtration, regardless of whether or not the oil was first degummed. However, such de-gumming will decrease the amount of foots present in the oil-foots mixture and can be advantageously used when separating by filtration.

If it is desired to filter the oil-foots mixture this can be done by closing a valve 73 and opening a valve 74 so that the mixture will flow to a filter 75. By way of example, this filter is shown as of the continuous rotary type including a trough-like pan 76 into which the mixture discharges. The usual rotatable drum 77 dips into this pan and provides a peripheral filter 78. A vacuum is maintained in a chamber 79 inside this drum by use of a vacuum pump 80 communicating therewith through a pipe 81 at one end of the drum. Such a vacuum forcibly draws refined oil through the filter 78, the foots being deposited thereon. This oil may be continuously withdrawn from the chamber 79 by a vacuum pump 82 through a pipe 83 communicating with the other end of this chamber. The foots are scraped from the filter 78 by a scraper 84 and move through a passage 85 to a conveyor housing 86. They are advanced therealong by a screw 87 rotating therein, being extruded through an extrusion means 88. In the event that the system is operated with the interior of the filter housing at sub-atmospheric pressure, this screw means will continuously withdraw the foots and increase the pressure thereon sufficiently to extrude these through the means 88.

If filtration is used, best results are obtained if the foots have been at least partially dehydrated. Substantially anhydrous foots can be easily separated by this type of filter, but if desired some moisture may be added thereto through the pipe 90.

It is often desirable to centrifugally separate the mixture of refined oil and foots. By closing the valve 74 and opening valves 73 and 91 this mixture may flow to a centrifuge 92. The usual high-speed centrifuge can be used, the refined oil and foots respectively discharging through spouts 93 and 94. However, superior separation, lower refining losses, and continuous operation over long periods of time can be effected by utilizing a heated centrifuge such as is disclosed in the application filed August 1, 1935, Serial No. 34,258, now Patent No. 2,100,277, granted November 23, 1937. For instance, a heating medium such as steam may be supplied through a pipe 95 to the exterior of the rotating bowl of the centrifuge.

If centrifugal separation is utilized, it is not desirable that the foots be completely anhydrous, otherwise continuous discharge thereof from the centrifuge cannot be satisfactorily effected. Such continuous operation can be insured by removing only a portion, or none, of the water by vaporization. On the other hand, if the foots have been substantially completely dehydrated, they can be re-hydrated to a desired extent as previously described. The foots need not be hydrated to the original degree to permit satisfactory separation, though the invention is not limited to the degree of hydration utilized.

It is also possible to separate the mixture of refined oil and foots by other means. For instance, by closing valve 91 and opening valve 96 the mixture may move into a gravitational separating means shown as including one or more tanks 97 from which the oil and foots can be separately withdrawn by means well known in the art.

While the invention has been described with reference to a continuous process, it will be clear that it is not limited thereto. The materials may be mixed in a refining kettle, preferably closed, and the alcohol or other de-emulsifying and inhibiting agent removed by vaporization, followed by separation of the oil and foots.

If continuous operation is used, the invention includes among its novel concepts the provision of a system in which the resulting mixture may be moved along a confined space, the de-emulsifying and inhibiting agent being vaporized and removed from one portion of this space. For instance, the pipe 20, the coil 26, and the chamber 34 may comprise this confined space. In this way, the de-emulsifying and inhibiting agent can be added to one portion of such a space and removed from another portion thereof. This permits recovery and re-use of such an agent with very small loss.

However, it will be clear that the invention is not in all instances limited to the use of a de-emulsifying and inhibiting agent. Even if not used, desirable results can often be obtained from the process in producing partially or completely dehydrated foots as a part of a continuous refining system. This dehydration of the foots often facilitates separation of the oil-foots mixture and stops saponification of neutral oil, also producing other desirable results.

I claim as my invention:

40 1. A process of refining a glyceride-type oil, which process includes the steps of: mixing proportioned quantities of said glyceride-type oil, an alkali refining reagent capable of reacting with the free fatty acids in said oil to form foots and added in amount greater than theoretically required for reaction with said free fatty acids, and a de-emulsifying and inhibiting agent selected from the group consisting of the lower aliphatic alcohols and their esters added in such amount as to minimize the saponification and entrainment of neutral oil; separating said de-emulsifying and inhibiting agent by vaporizing the same from the resulting mixture, leaving a mixture of refined oil and foots; and separating the foots and the refined oil.

55 2. A process of refining a glyceride-type oil, which process includes the steps of: removing gums and mucilaginous matter from said oil; mixing proportioned quantities of said glyceride-type oil, an alkali refining reagent capable of reacting with the free fatty acids in said oil to form foots and added in amount greater than theoretically required for reaction with said free fatty acids, and a de-emulsifying and inhibiting agent comprising a lower aliphatic alcohol added in such amount as to minimize the saponification and entrainment of neutral oil; separating said de-emulsifying and inhibiting agent by vaporizing the same from the resulting mixture, leaving a mixture of refined oil and foots; and separating the foots and the refined oil.

70 3. A process of refining glyceride-type oils which includes the steps of: continuously mixing in a confined space proportioned streams of said glyceride-type oil, an alkali refining reagent

capable of reacting with the impurities in said oil to form foots, and a de-emulsifying and inhibiting agent comprising a lower aliphatic alcohol used in such amount as to minimize the saponification and entrainment of neutral oil; continuously separating said agent from the resulting mixture by vaporizing said agent from said mixture to leave a mixture of refined oil and foots; and separating said refined oil from said foots.

10 4. A process of refining a glyceride-type oil which includes: removing gums and mucilaginous matter from said oil; continuously introducing into a confined space a stream of the oil thus preliminarily treated; continuously introducing into said confined space and mixing with said preliminarily treated oil therein proportioned quantities of an alkali refining reagent capable of reacting with the free fatty acids of said oil to form foots, and a de-emulsifying and inhibiting agent comprising a lower aliphatic alcohol used in such amount as to minimize saponification and entrainment of neutral oil; continuously separating said agent from the resulting mixture by vaporizing said agent from said mixture to leave a mixture of refined oil and foots; and separating said refined oil from said foots.

15 5. A process of refining glyceride-type oils which includes the steps of: continuously introducing into a confined space and mixing therein proportioned quantities of said glyceride-type oil, an alkali refining reagent capable of reacting with the impurities in said oil to form foots, and a vaporizable agent selected from the group consisting of the lower aliphatic alcohols and their esters, to form a mixture which is moved along said confined space; heating said mixture during flow through said confined space; continuously vaporizing said vaporizable agent and removing the resulting vapor from one portion of said confined space; continuously removing a mixture of refined oil and foots from another portion of said confined space; and separating said refined oil and said foots thus continuously removed.

20 6. A process of refining glyceride-type oils which includes the steps of: introducing into a confined space and mixing therein proportioned quantities of said glyceride-type oil, an alkali refining reagent capable of reacting with the impurities in said oil to form foots, and a vaporizable agent selected from the group consisting of the lower aliphatic alcohols and their esters, to form a mixture which is moved continuously along said confined space; continuously introducing the resulting products into a low-pressure zone; removing said agent in vapor state from said low-pressure zone; continuously removing the resulting vapor from said low-pressure zone; continuously removing a mixture of refined oil and foots from said zone without impairing the low pressure therein; and separating said refined oil and said foots.

25 7. A process of refining glyceride-type oils which includes the steps of: continuously introducing and mixing in a relatively confined space closed from the atmosphere proportioned streams of said glyceride-type oil, an alkali refining reagent capable of reacting with the impurities in said oil to produce foots, and a vaporizable agent selected from the group consisting of the lower aliphatic alcohols and their esters, thus forming a mixture which is moved continuously along said confined space; heating said mixture during flow through said confined space; con-

tinuously introducing the heated mixture into a larger zone closed from the atmosphere and without exposing said heated mixture to the atmosphere before introduction thereinto; continuously removing vapors of said agent from said larger zone to leave a mixture of refined oil and foots; continuously removing said mixture of refined oil and foots from said larger zone; and separating said refined oil and said foots.

8. A process of refining glyceride-type oils which includes the steps of: continuously mixing in a confined space proportioned streams of said glyceride-type oil, an alkali refining reagent capable of reacting with the impurities in said oil to form foots, and a lower aliphatic alcohol, the quantity of said refining reagent being in excess of that required to react with the free fatty acids, and the quantity of said alcohol being sufficient to minimize saponification and entrainment of neutral oil; continuously moving the resulting mixture through said confined space, thus permitting the excess refining reagent to act upon the color impurities of said oil while said alcohol is present; continuously separating the alcohol from the resulting reaction products to leave a mixture of refined oil and foots; returning at least a portion of the thus separated alcohol to said confined space to form at least a portion of the proportioned stream of alcohol delivered thereto; and separating said refined oil and said foots.

9. A process of refining glyceride-type oils which includes the steps of: mixing in a space closed from the atmosphere proportioned quantities of glyceride-type oil, an aqueous alkali refining reagent capable of reacting with the impurities in said oil to form foots; and a vaporizable de-emulsifying and inhibiting agent comprising a lower aliphatic alcohol, thus forming reaction products including oil, water, foots, and said agent; vaporizing said agent and at least a portion of said water from said reaction products during flow through a confined space to at least partially dehydrate said foots; removing from said confined space said vapors of said agent and water to leave a mixture of refined oil and foots which have been at least partially dehydrated; and separating the foots from said refined oil.

10. A process of refining glyceride-type oils which includes the steps of: forming a mixture in a space substantially closed from the atmosphere of proportioned quantities of said glyceride-type oil, an alkali refining reagent capable of reacting therewith to form foots, and a vaporizable agent selected from the group consisting of lower aliphatic alcohols and their esters; introducing a stream of the resulting reaction products into a low-pressure zone; applying heat to said low-pressure zone to vaporize said agent; withdrawing the resulting vapors from said low-pressure zone; and separating said foots from the refined oil.

11. A process of refining glyceride-type oils which includes the steps of: bringing together in mixing relationship in a confined space proportioned streams of a glyceride-type oil, an alkali refining reagent capable of reacting with the impurities of said oil to form foots, and a vaporizable de-emulsifying and inhibiting agent comprising a lower aliphatic alcohol; continuously vaporizing said de-emulsifying and inhibiting agent by heating a stream of the resulting mixture and introducing same into a separating zone; continuously removing the resulting vapors from said separating zone to leave a mixture of refined oil

and foots and filtering said foots from said refined oil.

12. A process of refining glyceride-type oils which includes the steps of: bringing together in mixing relationship in a confined space proportioned streams of a glyceride-type oil, an alkali refining reagent capable of reacting with the impurities of said oil to form foots, and a vaporizable de-emulsifying and inhibiting agent comprising a lower aliphatic alcohol; continuously vaporizing said de-emulsifying and inhibiting agent by heating a stream of the resulting mixture and introducing same into a separating zone; continuously removing the resulting vapors from said separating zone to leave a mixture of refined oil and foots; and subjecting a stream of said mixture of refined oil and foots to a centrifugal separating action to separate said foots from said refined oil.

13. A process of refining glyceride-type oils containing fatty acids, which process includes the steps of: neutralizing said fatty acids in the presence of not more than a few per cent of a lower aliphatic alcohol; then vaporizing the alcohol while maintaining the foots uniformly dispersed in the oil; and then separating the foots from the oil.

14. A process as defined in claim 13 in which said alcohol is separated by vaporization while the mixture containing oil, foots and alcohol is subjected to a subatmospheric pressure.

15. A process of refining glyceride-type oils containing fatty acids, which process includes the steps of: preheating said oil; neutralizing the fatty acids in the pre-heated oil in the presence of not more than a few per cent of ethyl alcohol; then vaporizing the alcohol while maintaining the foots uniformly dispersed in the oil; and then separating the foots from the oil.

16. A process of refining a glyceride-type oil, which process includes the steps of: mixing proportioned quantities of said glyceride-type oil, an alkali refining reagent capable of reacting with the free fatty acids in said oil to form foots and added in amount greater than theoretically required for reaction with said free fatty acids, and a de-emulsifying and inhibiting agent comprising a lower aliphatic alcohol which is more volatile than the oil and which is added in such amount as to minimize the saponification and entrainment of neutral oil; vaporizing said de-emulsifying and inhibiting agent from the resulting mixture, leaving a mixture of refined oil and foots; and separating the foots and the refined oil.

17. A process of refining a glyceride-type oil, which process includes the steps of: removing gums and mucilaginous matter from said oil; mixing proportioned quantities of said glyceride-type oil, an alkali refining reagent capable of reacting with the free fatty acids in said oil to form foots and added in amount greater than theoretically required for reaction with said free fatty acids, and a de-emulsifying and inhibiting agent comprising a lower aliphatic alcohol which is more volatile than the oil and which is added in such amount as to minimize the saponification and entrainment of neutral oil; vaporizing said de-emulsifying and inhibiting agent from the resulting mixture, leaving a mixture of refined oil and foots; and separating the foots and the refined oil.

18. A process of refining glyceride-type oils which includes: continuously introducing into a confined space and mixing therein proportioned quantities of a glyceride-type oil, an alkali refin-

ing reagent capable of reacting with the free fatty acids in said oil to form foots, and a de-emulsifying and inhibiting agent comprising a lower aliphatic alcohol which is more volatile than the oil and which is used in such amount as to minimize the saponification and entrainment of neutral oil; vaporizing said agent from said mixture in said confined space; continuously removing the vapor of said agent from said confined space to leave a mixture of refined oil and foots; and separating said foots from said refined oil.

19. A process of refining a glyceride-type oil which process includes: mixing proportioned quantities of said glyceride-type oil, an alkali refining reagent capable of reacting with the free fatty acids of said oil to form foots and added in quantity in excess of that theoretically necessary to react with said free fatty acids, and a de-emulsifying and inhibiting agent, comprising a lower aliphatic alcohol which is more volatile than the oil and which is added in sufficient quantity to minimize the saponification and entrainment of neutral oil; continuously moving the resulting mixture along a passage closed from the atmosphere; vaporizing said de-emulsifying

and inhibiting agent from the resulting mixture while in said passage and removing the resulting vapors from said passage to leave a mixture of refined oil and foots; and continuously separating said foots from the refined oil.

20. A process of refining glyceride-type oils which includes the steps of: continuously bringing together in mixed relationship in a confined space proportioned streams of a glyceride-type oil, an alkali refining reagent capable of reacting with the impurities of said oil to form foots, and a vaporizable de-emulsifying and inhibiting agent comprising a lower aliphatic alcohol to form a stream of products moving along said confined space; continuously vaporizing said agent from said stream during movement in said confined space to leave a mixture of refined oil and foots substantially free of said agent; continuously removing the vapors of said agent from said confined space; and subjecting a stream of said mixture of refined oil and foots to centrifugal force while applying heat to the zone in which the centrifugal force is applied, thereby continuously separating the foots from the refined oil.

BENJAMIN CLAYTON.
